UNITED STATES PATENT OFFICE.

JOSEPH M. LAUBE, OF BELLINGHAM, WASHINGTON.

HEATING FURNACE.

Application filed October 30, 1922. Serial No. 597,929.

To all whom it may concern:

Be it known that I, JOSEPH M. LAUBE, a citizen of the United States, and a resident of Bellingham, in the county of Whatcom and State of Washington, have invented a new and useful Heating Furnace, of which the following is a specification.

The object of my improvement is to provide a tight-wall furnace having a radiator with interior hot-gas directing means, operable from the exterior, by which the course of the gases is changed from direct to indirect by easily operable and replaceable parts which have great endurance.

I attain this object with the devices illustrated in the three sheets of accompanying drawings in which Figure 1 is a front elevation of a pipeless, hot-air furnace embodying my improvements. Fig. 2 is a side elevation of Fig. 1 partly in section on a vertical medial plane. Fig. 3 is a front elevation of the humidifying device drawn on a larger scale. Fig. 4 is a side elevation of Fig. 3 partly in section on a medial vertical plane. Fig. 5 is a side elevation of the front end of the fire pot and ash pit partly broken away and drawn on a larger scale. Fig. 6 is an elevation view in vertical section of one of the exterior-wall plate, air-tight joints drawn on a larger scale. Fig. 7 is a bottom plan view of Fig. 6. Fig. 8 is a horizontal section of one of the corner joints of the exterior walls drawn on a larger scale.

Similar characters refer to similar parts throughout. Certain parts are broken away to show other parts hidden thereby.

The term "air-tight" as used throughout this specification is properly applicable under the difference of pressure pertaining between the inner and outer sides of the exterior walls of heating furnaces.

More particularly: My furnace is preferably of rectangular horizontal cross section. As illustrated, the front wall is at 8, the rear wall at 9, and the exterior side walls at 10, 10, and the furnace bottom wall plate at 11. The top of the furnace is drawn in to form a truncated pyramid the outer walls of which are indicated by 12, and on top of this rests grating 13 which is usually flush with the top floor surface of the room to be heated. The stove bolts used to fasten the several parts of the walls together are indicated by 14, as in Figs. 6-8, which illustrate my method of making an air-tight joint well adapted for factory-made goods

which are to be shipped in knocked-down shape. Figs. 6 and 7 show a joint used to connect the edges of the horizontal seam between the bottom and top parts of side plates 10. The lower edge of the upper plate is bent outward at right angles, then it is bent upward at b^{10} at an angle of about 30°, then downward at c^{10} to enclose an angle of about 60°, then its edge is folded over inwardly at d^{10} . The upper edge of the lower plate is bent outward at an angle of 90° and its edge bent upward at e^{10} at an angle of about 10° to lie in angle c^{10} . The edges of the plates 10 are set together to bring them in the same plane and a row of spaced, registering bolt holes made through their adjacent edges. Round asbestos wicking 15 is placed in angle c^{10} beneath edge e^{10} and the joint is sealed thereby when bolts 14 tightly clamp the two edges together. It is readily understood that this joint is easily formed on a tinner's brake in plates suitably heavy for the purpose intended. Also the plates to be joined by these connections are readily assembled at the place of installation. The air-tight joint used for making the plate connections at the vertical corners between front and back and side plates is shown in Fig. 8 in horizontal section. This illustration will require no further explanation because of its similarity to the one above described. The joint shown in Fig. 8 is also adapted for joining bottom plate 11 and front, back and side plates, 8, 9, 10 and 10, respectively. Also the joint shown in Figs. 6 and 7 is suited for connecting said front, back and side plates with furnace top 12 by a slight change in the angularity. The corners of furnace top 12 are lock joints of usual construction. Within said top at its upper end is centrally placed short, hollow cylinder b^{16} which is joined with a locked seam with the top of a downwardly flaring connection 16, a^{16} , the opposite sides a^{16} of which are riveted along their lower edge tightly to the front and rear sides of top 12 near their lower edge, and flaring sides 16 are joined along their lower edges to the upper edge of inner wall plates 18, 18, leaving cold air flues 17, 17 between said flaring connection and the side walls of top 12. Inner side walls 18, 18, as stated, are connected along their upper edges with the lower edges of the sides of flaring connection 16, 16 and extend downward to within about one foot of furnace bottom 11. The

vertical edges of said inner walls are bent over at right angles and the edges thus turned are bolted to front and rear plates 8 and 9 at a distance from side plates 10 to form the lower part of cold air flues 17, 17. The space between said inner walls 18, 18 and front and rear outer walls 8 and 9 together with the space enclosed by connection 16, a^{16} and ring b^{16} is the central chamber or hot-air flue of the furnace. The furnace front is shown at 20 having ash-pit door 21 and fire-box door 22 hinged thereon. Draft door a^{21} is hinged along its upper edge to ash-pit door 21 and covers a draft opening through said door. Check draft damper a^{22} is pivoted to the front of door 22 and controls the admission of air through openings in said door. Shield 23 having triangular sides a^{23} , a^{23} is fastened to the 20 inside wall of fire-box door 22, and not only protects said door from the furnace heat, but causes air, passing through door 22, to first cool shield 23 and then pass from behind the shield below its bottom and enter the fire pot close to the fuel within the same and pass rearward over the top of said fuel providing oxygen for a slow combustion, the ashes from which will aid in covering said fuel to aid in checking said burning. Furnace front 20 is bolted to the flange a^{29} of fire box 29 and ash pit 30 and to front plate 8 of the furnace with asbestos gasket 31 between said furnace wall and said flange. This closure seals the joint between said 35 wall 8 and flange a^{29} against the passage of air. Front plate 24 of water pan 25 extends as a flange beyond said pan and is bolted to front furnace plate 8 with asbestos gasket 28 between to seal the joint against the passage of air. Funnel 26 has pipe nipple 27 welded to its rear wall near its bottom and this pipe enters a hole through plate 24 into pan 25 near its bottom. A gasket is placed between funnel 26 and plate 40 24 and between said plate and the nut of nipple 27 and around said nipple to cause a water-tight connection and joint around said pipe where it passes through plate 24. A cover a^{26} is fitted over the top of funnel 26. A small quantity of water in pan 25 is sufficient to stand above pipe 27 and seal the connection between said funnel and pan against the passage of air therethrough. Fire box 29, when for a wood-burning furnace, is preferably cylindrical and placed horizontally in the central furnace chamber near its bottom. Ash pit 30 is welded to fire box 29 and its side walls are extended to form the neck of fire box 29 at b^{29} and flanged at a^{29} for clamping to furnace front 20 as described above. Wall c^{29} provides a partition between neck b^{29} and ashpit 30. 31 is the asbestos gasket between flange a^{29} and front wall 8 as described above. Return flue radiator 32 is preferably a hollow cyl-

inder and placed in a horizontal position above fire box 29 with which it has flue connection through nipple 36 cemented in double walled nipple 35, a^{35} . To the front end of radiator 32 is welded nipple 33 which protrudes through a hole in front plate 8. This nipple is elliptoconical and a substantially air-tight joint is made with plate 8 by making the hole through said plate smaller than said cone and flaring said plate outward in a curved flange around said hole and then driving said plate on said conical nipple by hammer blows on said flange. When properly done this joint is tight against the passage of air under the pressures existing. Nipple 33 is closed by cover a^{33} . Smoke pipe nipple 34 is welded to the rear end of radiator 32 and protrudes through rear wall 9 with which it makes an air tight closure by means of curved flange b^9 . Nipples 35 and 36 join to provide a flue connection between the firepot and the radiator as described. Two sets of brackets 37 are fastened to opposite sides of the interior walls of radiator 32. On each set of said brackets is placed horizontally one of radiator damper side plates or slideway plates 38. Said plates preferably have pins 39 which engage in holes in brackets 37. Plates 38 are narrow and serve as slideways for the damper. Each has a rib a^{38} on its upper side and facing edge and on these ribs is mounted damper 40. Side plates 38 are substantially as long as the radiator. But damper 40 is shorter than said radiator by the width of the opening desired for the passage of smoke through the radiator. Said damper 40 is reciprocable longitudinally on its slideways and its position in the radiator determines the course of the smoke through the radiator. If the damper is close to the front end of the radiator, the smoke passes directly through the rear end of the radiator into the stack; if the damper is close to the rear of the radiator, the smoke must pass horizontally through the lower half of the radiator beneath the side plates 38 and damper 40 to the front end of the radiator where it rises past the front end of the damper and then passes rearward above the damper and side plates and into said stack; and if the damper occupies a medial position lengthwise of the radiator, said smoke divides and passes over both of said paths. The damper 40 is shown in full lines in Fig. 2 in its rear position and in dotted lines at 40' in its forward position. In a hole through damper 40 is engaged hook 42 of damper rod 41, and said damper rod is mounted in a hole through nipple cover a^{33} and has handle a^{41} exterior to said cover. Damper 40 is settable in any desired position within its range of movement in the radiator by means of rod 41. When desired damper 40 can be removed from 130

radiator 32 by removing cover α^{33} , and withdrawing said damper, then, if desired, rod 41 can be disengaged from the damper at hook 42. Also each of damper plates 38 can be removed by hand through nipple 33. When thus cleared radiator 32 can easily be cleaned with a proper utensil by shoving the accumulated ashes and soot backward to fall into the firebox through nipples 35 and 36, and, if said damper and side plates are worn out, their replacement with new ones is easily accomplished. An opening is placed in each of side walls 10 near the bottom through which dust can be removed from the furnace floor. These openings are reinforced on the interior of said side walls 10 by frames 44 which have tapped holes for clamping screws to retain covers 43 in place on gaskets 45. In this manner an air-tight closure is provided for these lower clean-out holes not difficult to remove and replace.

My sectional damper plate made of substantial dimensions and material with its sliding-section and easy-removable features has been found to be a good solution for this difficult part of the furnace design.

Having thus disclosed my invention, what I claim as new and desire to secure by Letters Patent is,—

1. In a heating furnace in combination, a combustion chamber, a radiator chamber above said combustion chamber the lower rear part of which has flue connection with said combustion chamber and the rear upper part of which has flue connection with a smoke pipe and having a clean-out opening in its front wall, a removable cap having a

small hole therethrough over said clean-out opening, two damper slideways removably mounted on the interior walls of said radiator to extend in slideway relation from the front to the rear thereof and located midway between the bottom and top thereof and adapted for installation and removal through said clean-out opening, a damper shorter than said radiator mounted therein for reciprocation on said damper slideways and adapted to pass through said clean-out opening for installation and removal, and a damper rod connected to said damper and mounted for reciprocation in said hole in said clean-out-opening cap.

2. In a heating furnace in combination, a radiator chamber the lower rear part of which has a flue connection with the combustion chamber of said furnace and the rear upper part of which has a flue connection with a smoke pipe and also having a clean-out opening in its front wall, a removable cap over said clean-out opening, removable damper slideways mounted on the inner walls of said radiator to extend in slideway relation from the front to the rear thereof and located midway between the bottom and top thereof and adapted for installation and removal through said clean-out opening, a damper shorter than said radiator and mounted therein for reciprocation on said damper slideways and adapted to pass through said clean-out opening for installation and removal, and means adapted to reciprocate said damper from outside said radiator.

JOSEPH M. LAUBE.
